METAL CHELATES OF OXAZOLIDINONES AS
CENTRAL NERVOUS SYSTEM STIMULANTS
Basil H. Candon, Clifton, and Max Chessin, Fair Lawn,

assignors, by mesne assignments, to The Purdue
Frederick Company, New York, N.Y., a corporation
of New York

Filed Mar. 22, 1960, Ser. No. 16,788
19 Claims. (Cl. 167—65)

The present invention relates to metal chelates of 2-imino-5-phenyl-4-oxo oxazolidine, hereinafter referred to as pheniminooxazolidinone, also known as 2-imino-5-phenyl-4-oxazolidinone which has the structural formula:

Pheniminooxazolidinone is recited to have certain central nervous system stimulating qualities (CNS) with low incidence of the side effects usually attendant upon the administration of arousing amines.

The subject matter of the present invention stems from the discovery that it is possible to form certain metal chelates of pheniminooxazolidinone having an unexpected structure, which share the superior CNS stimulating characteristics of pheniminooxazolidinone but which surprisingly exhibit, among other advantages, a higher order of activity, an earlier onset of action, greater evenness and reliability of therapeutic action, and a broader response.

The metal pheniminooxazolidinone chelates were prepared by raising the pH of an aqueous or hydroalcoholic solution of pheniminooxazolidinone to 11 or more and then adding an aqueous solution of an appropriate metal salt, selected from salts of magnesium, copper and iron from which solution there is precipitated the corresponding metal chelate of pheniminooxazolidinone.

The fact that the chelates formed are N,N'-chelates, i.e. bond with the two nitrogen atoms to form a four-membered ring, was surprising in view of the fact that from a consideration of the structure of pheniminooxazolidinone it would have been expected that the bonding would be between the number 3 nitrogen atom and the carbonyl oxygen atom. This is especially true in the case of magnesium chelates. Of course, the number of water molecules comprising the water of chelation consists of the difference between the number of coordinate bonds of the chelated metal molecule which are otherwise filled, as by the bonding of the metal into the chelate ring, and the coordination number of the metal. Water of hydration also may be present as, for example, in the case of the magnesium chelate.

Pharmacological studies conducted with the magnesium chelate of pheniminooxazolidinone indicate that it induces CNS stimulation in monkeys, dogs, cats, rabbits, rats and mice, the duration and degree of activity depending upon the dose administered. For example, the minimal effective dose on the overt behavior on the rhesus monkey is 2.5 to 5 mg. per kg. on oral administration, while the duration of hyperactivity was from 6 to 8 hours. With increasing doses the increased locomotor activity was prolonged. Thus, when 10 to 25 mg. per kg. were administered by mouth the duration of activity was extended to the range of 48 to 72 hours. Even with the higher dosages the absence of side effects was noted.

The oral LD₅₀ in mice was determined to be approximately 1500 mgs. per kg.

A comparative acute toxicity study done in male al-

2

bino rats, wherein oral doses of pheniminooxazolidinone and pheniminooxazolidinone magnesium chelate were given suspended in a 5% aqueous gum acacia solution (administered in the fasting state), employing a 4-dose assay and 10 rats per dose level, revealed the following one-week results:

Pheniminooxazolidinone—LD₅₀ = 550 mg./kg. (standard error: 0.035; limits of error: 85% to 117%)

Magnesium chelate of pheniminooxazolidinone—LD₅₀ = 550 mg./kg. (standard error: 0.035; limits of error: 85% to 117%)

The above results were calculated according to Graphic Analysis method of E.J. De Beer, *J. Exptl. Pharmacol. & Therap.* 85: 1-13 (1945).

It is notable that although the results in the LD₅₀ comparative studies above undertaken are equivalent, the magnesium chelate contains approximately 70% of the pheniminooxazolidinone as active moiety and hence the studies indicate that on the basis of the amount of such active moiety the chelate is substantially more active than the original base.

To measure the onset and duration of effect of the magnesium chelate compared to the pheniminooxazolidinone, screening studies with mice, based on the response to supramaximal electroshock were undertaken.

Mice received supramaximal electroshock (alternating current) through corneal electrodes. The latency period is measured for convenience from onset of shock to onset of tonic extensor phase. It includes normally a phase of increasing limb flexion. The threshold for tonic extensor convulsions is 7-10 mA. The latency period between shock and the extensor component of the convulsion was recorded to the nearest 0.2 second following 20 mA. (approximately twice the threshold shock).

After establishing that pheniminooxazolidinone and magnesium pheniminooxazolidinone significantly prolonged the supramaximal electroshock latency period following oral administration, the drugs were administered orally to mice, generally in groups of 20. Treated groups and control groups were challenged at scheduled intervals and onset and duration of action compared. Dose for each compound was 100 mg./kg. p.o. Analysis of data presented in Table I following (statistical analysis—"t" test for significance: P=0.05) reveals that the magnesium chelate of pheniminooxazolidinone is more rapidly effective than pheniminooxazolidinone. The onset of activity of the chelate was significant at 15 minutes while pheniminooxazolidinone was not effective at 1/4 or 1/2 hour after treatment—its significant statistical activity first appeared at one hour.

TABLE I

Expt. #	Time of Electroshock Challenge after drug in hrs. (100 mg./kg. p.o.)	No. Mice per group	Increase in seizure latency time over control group	
			Mg. Chelate Phenimino-oxazolidinone	Phenimino-oxazolidinone

11.....	10	10	N.S.....	N.S.

Note.—S=Statistically significant increase in latency seizure time.
N.S.=not significant statistically ("t" test).

The details of electroshock seizure latency experiments may be obtained from: Seizure Latency and Antipsychotic

Drugs by J. E. P. Toman, G. M. Everett, and R. F. Jeans, Tranquillizing Drugs, published by American Association for the Advancement of Science, Washington, D.C., 1957 ed., by Dr. Harold E. Himwich, pp. 23 to 33; and J. E. P. Toman, G. M. Everett and A. H. Smith, Jr., 1954 Experimental and Other Factors Modifying Electroshock Seizures in Mice, Am. J. Physiol. 179, 680.

Clinical studies made with magnesium chelate of pheniminoxazolidinone confirm the chronological evidence detailed above to the effect that the onset of action of the magnesium chelate of pheniminoxazolidinone is substantially quicker than the corresponding onset of action of pheniminoxazolidinone. It establishes as well the fact that a lower dosage of the magnesium chelate provides the desired therapeutic response. In clinical studies made to date it has been found that the required dosage of magnesium chelate was $\frac{5}{7}$ to $\frac{5}{6}$ of that required of pheniminoxazolidinone. This in itself is an unexpected result since chelates are usually less active than the compounds from which they are derived.

The decided advantage of the magnesium chelate over the pheniminoxazolidinone is its even response which contrasted to the sometimes erratic results obtained with pheniminoxazolidinone. For example, in one study eleven persons who did not respond to pheniminoxazolidinone responded favorably to the magnesium chelate. Investigators uniformly commented that in the employment of the magnesium chelate as an arousal agent, as distinguished from the employment of pheniminoxazolidinone, more consistent success was achieved with the magnesium chelate.

The uniform dosage preferred was in the range of 50 to 100 mg. with the optimum daily dosage approximately 100

ings were neutral to litmus, followed by a small quantity of acetone, dried and powdered. The yield was 59 g. or 90%. The magnesium chelate resulting has the following structural formula:

5

10 The empirical formula is $C_9H_{10}N_2O_4MgH_2O$. The molecular weight is 252.5.

Microanalysis showed the following—

Calculated for $C_9H_{10}N_2O_4MgH_2O$: C, 42.81; H, 3.99;

15 N, 11.09; $3H_2O$, 21.43; $2H_2O$ (coordinated), 15.70; Mg, 9.64. Found: C, 42.0; H, 4.3; N, 9.9; $3H_2O$, 2053; $2H_2O$, 15.76; Mg, 10.4.

Total water determination using the Karl Fischer method—

Calculated: $3H_2O$, 2143%. Found: $3H_2O$, 20.53%.

20 Determination of water of chelation by drying a sample at 250° C., after first drying at 100° C. to remove any water of hydration—

Calculated: $2H_2O$, 15.70%. Found: $2H_2O$, 15.76%.

The compound appears as a white, odorless amorphous 25 substance having a melting point greater than 300° C.

The fact of chelate formation is clearly indicated during synthesis by a drop in pH from 11.5 to 5 upon the addition of magnesium sulfate. This shows rapid hydrogen release and chelate formation.

30 Magnesium chelate is found to be practically insoluble in water and other solvents, not stable to acids but stable with respect to alkali, heat, air and light. Compared to pheniminoxazolidinone its characteristics are as follows:

TABLE II

M. P., ° C.	Solubility in H_2O (25° C.), γ/ml.	Solubility in KOH, 5%	Oil-Water Partition Coefficient	Reaction with m-dinitrobenzene	Treatment with dilute HCl and heat
Pheniminoxazolidinone 256.	50	Soluble....	3.2	Pink Color.....	Converted to phenyl-diketotetrahydrooxazole.
Magnesium Chelate of Pheniminoxazolidinone 300.	70	Insoluble..	4.23	No color change...	Decomposition.

mg. Dosages from 15 through 180 mg. were administered with significant results.

In addition to administration for conditions described for pheniminoxazolidinone in U.S. Patent No. 2,892,753, it was found that the magnesium chelate had unexpected utility in the treatment of narcolepsy, petit mal epilepsy, barbiturate and alcoholic hangovers, and antisocial disorders. Investigators who had worked with pheniminoxazolidinone remarked upon the earlier onset of action of magnesium chelate of pheniminoxazolidinone.

The invention is further illustrated by the following examples which disclose illustrative methods of preparation of the compounds useful in the present invention.

EXAMPLE 1

Bisquo (2-Imino-5-Phenyl-4-Oxazolidinone-N,N') Magnesium (II) Hydrate (Magnesium Chelate of Pheniminoxazolidinone)

To 44 g. (0.25 mole) of pheniminoxazolidinone was added 500 ml. of ethanol and 60 ml. of 20% sodium hydroxide solution with rapid stirring. Following complete solution of the pheniminoxazolidinone the solution was diluted with one liter of distilled water. A solution of 62 g. (0.25 mole) of magnesium sulfate, U.S.P., in 200 ml. of water was slowly added over a period of five minutes alternately along with 55 ml. of 20% sodium hydroxide to return the pH to 11. The resulting mixture was stirred for one hour, allowed to settle over night, the clear aqueous solution decanted and the product obtained by filtration. The product was washed with water until the wash-

The table indicates quite clearly that a new molecule is involved with substantially different characteristics. Of particular interest from the pharmaceutical point of view is the difference in oil/water partition coefficients. The 50 procedure followed in establishing the coefficients was as follows:

Commercial oleyl alcohol (Du Pont Co., B.P. 137-142°/2 mm.) was used to partition the compounds between it and water at 25°. A saturated aqueous solution of each compound was prepared and readings taken with the spectrophotometer. To 50 ml. of a saturated aqueous solution of each compound was added an equal volume of oleyl alcohol. The mixture was magnetically stirred at varying intervals for three days. A portion of the water layer was then removed and filtered through Filter-Cel to remove residual droplets of oil. The concentration of each compound in the water was then determined spectrophotometrically.

The following oil/water partition coefficients were obtained by use of a Beckman DU spectrophotometer at two wavelengths:

	250 m μ	260 m μ
70 Pheniminoxazolidinone.....	3.20	3.20
Magnesium Chelate of Pheniminoxazolidinone.....	4.26	4.30

It is believed that at least in part the difference in oil/water partition coefficients accounts for the increased 75 biological activity of the magnesium chelate and for its

earlier onset of action, since a higher oil/water partition coefficient is usually taken to indicate greater and more rapid cell penetration.

Illustrative of other magnesium salts which may be employed in lieu of magnesium sulfate are the following: magnesium bromide, magnesium chloride, magnesium citrate, magnesium nitrate, magnesium acetate and magnesium phosphate.

FIG. 1 is a tracing of the infrared absorption curve of the magnesium chelate (0.3% in KBr).

FIG. 2 shows a similar tracing for pheniminoxazolidinone.

The spectra clearly show the difference in the two molecules and evidence as well the site of chelation. The two spectra are essentially the same except for the effects shown by chelation. The carbonyl band at 1720 cm^{-1} and the

at 3000 cm^{-1} are not changed in the magnesium chelate. There is present in FIG. 1 a weak absorption band at 660 cm^{-1} which may be assigned to metal donor vibrations. The slight increase in absorption in the 1500 cm^{-1} region shown in FIG. 1 indicates coordination at the $\text{C}=\text{N}$ position. The strong absorption band at 3600 cm^{-1} may be assigned to water of coordination.

Significantly, the five-membered ring of the pheniminoxazolidinone is not altered by the formation of the magnesium chelate. It is believed that this ring in unaltered form is necessary to the biological action of both components.

EXAMPLE 2

Bisquo-(2-Imino-5-Phenyl-4-Oxazolidinone-N,N')-Copper (II) (Copper Chelate of Pheniminoxazolidinone)

To a solution of 0.9 gm. (0.005 mole) of pheniminoxazolidinone in water or a water:alcohol mixture at a pH of 11 was added 0.65 gm. (0.005 mole) of CuCl_2 , in a small quantity of water. An immediate drop in pH was noted (indicating chelate formation) and brought back to 10 with dilute NaOH. The fact of chelation is dramatically evidenced during synthesis by the marked color change from colorless to blue. Stirring was continued for one hour, followed by filtration of the blue precipitate. The product was washed with water, acetone and then dried. The yield was 92% based on the proposed structure. The copper chelate resulting has the following structural formula:

The empirical formula is $\text{C}_9\text{H}_{10}\text{N}_2\text{O}_4\text{Cu}$, the molecular weight 273.7.

Microanalysis showed the following—

Calculated for $\text{C}_9\text{H}_{10}\text{N}_2\text{O}_4\text{Cu}$: C, 39.49; H, 3.68; N, 10.23; Cu, 23.21. Found: C, 40.90; H, 3.6; N, 9.9; Cu, 22.3.

The copper chelate is an amorphous blue, odorless compound decomposing above 200°, which is insoluble in water and other solvents, and is not stable to acids but is stable to alkali, heat, below 200°, air and light.

As in the case of the magnesium chelate, other copper salts may be substituted for the copper chloride used above.

EXAMPLE 3

Trisquo-(2-Imino-5-Phenyl-4-Oxazolidinone-N,N')-Iron (III) Hydroxide. (Iron Chelate of Pheniminoxazolidinone)

Iron chelate of pheniminoxazolidinone is prepared in the same manner as copper chelate of pheniminoxazolidinone, as described in Example II, except that ferric sul-

fate is substituted for copper chloride. The yield was 92% based on the proposed structure. The iron chelate resulting has the following structural formula:

5 The empirical formula is $\text{C}_9\text{H}_{13}\text{N}_2\text{O}_6\text{Fe}$, the molecular weight 301.0.

Microanalysis showed the following—

Calculated for $\text{C}_9\text{H}_{13}\text{N}_2\text{O}_6\text{Fe}$: C, 35.91; H, 4.35; N, 9.31; Fe, 18.55. Found: C, 35.5; H, 3.9; N, 8.9; Fe, 19.2.

15 The iron chelate is an amorphous light brown, odorless compound, decomposing above 200°, very slightly soluble in water and other solvents, not stable to acids but stable to alkali, heat below 200°, air and light.

As in the case of the magnesium chelate and the copper chelate, other iron salts may be substituted for the ferric sulfate used above.

The examples which follow illustrate the preparation of pharmaceutical compositions according to the present invention without, however, being limited thereto.

EXAMPLE 4

Tablets

30 12.5 gms. of the magnesium chelate of pheniminoxazolidinone, 28.4 gms. of lactose, and 8.2 gms. of starch are mixed for 30 minutes. The mixture is granulated with a solution containing 0.4 gm. of gelatin in 11 mls. of demineralized water and 0.25 gm. of silicon emulsion. The granulate is broken up, dried at 50° C., and mixed for 35 10 minutes. 0.5 gm. of amylopectin is added and the mixture compressed into tablets. With a loss on drying of 0.25 gm., the yield is approximately 490 tablets, each weighing 100 mg and containing 25 mg. of the drug.

EXAMPLE 5

Capsules

40 12.5 gms. of the magnesium chelate of pheniminoxazolidinone is triturated intimately with 42.5 gms. of lactose. The resultant mixture is packed into the base of hard gelatin capsules (#5) and the cap closed securely. The yield is approximately 500 capsules, each weighing 110 mg. and containing 25 mg. of the drug.

EXAMPLE 6

Suppositories

50 (a) 22.5 gms. of the magnesium chelate of pheniminoxazolidinone is levigated with 300 mg. of polyethylene glycol (1500).

(b) 500 gms. of polyethylene glycol (6000) is melted and 200 gms. of polyethylene glycol (400) added to it.

(a) and (b) are combined with stirring and the resultant mixture is poured into molds and allowed to cool. The yield is approximately 450 suppositories, each weighing approximately 2.2 gms. and containing 50 mg. of the drug.

EXAMPLE 7

Suspension

65 5.0 gms. of the finely powdered magnesium chelate of pheniminoxazolidinone is triturated with a few mls. of syrup, U.S.P. (modified with coloring, flavoring and preserving agents). The mixture is diluted gradually to 1000 mls. Each teaspoonful (5 mls.) of the suspension contains 25 mg. of the drug.

70 In the above examples of pharmaceutical preparations the unit dosage has been set at 25 mg. It has been found that this is an ideal and flexible unit dosage of active material, although, as brought out above, unit dosages of from 15 through 200 mg. have been found to be effective.

7
EXAMPLE 8

For the magnesium chelate of pheniminooxazolidinone in Examples 4 through 7 there may be substituted the copper and iron chelates of pheniminooxazolidinone, the quantity being varied in accordance with standard compounding practices to produce unit dosage forms containing 25 mg. of the drug.

It is not desired to be limited except as set forth in the following claims, the above description being by way of illustration of the invention.

What is claimed is:

1. A metal chelate of 2-imino-5-phenyl-4-oxazolidinone selected from the group consisting of 2-imino-5-phenyl-4-oxazolidinone-N,N'-magnesium, 2-imino-5-phenyl-4-oxazolidinone-N,N'-copper and 2-imino-5-phenyl-4-oxazolidinone-N,N'-iron.
2. 2-imino-5-phenyl-4-oxazolidinone-N,N'-magnesium.
3. 2-imino-5-phenyl-4-oxazolidinone-N,N'-copper.
4. 2-imino-5-phenyl-4-oxazolidinone-N,N'-iron.
5. The method of preparing a metal chelate of 2-imino-5-phenyl-4-oxazolidinone selected from the group consisting of the 2-imino-5-phenyl-4-oxazolidinone-N,N'-magnesium, 2-imino-5-phenyl-4-oxazolidinone-N,N'-copper and 2-imino-5-phenyl-4-oxazolidinone-N,N'-iron which comprises the steps of elevating a solution of 2-imino-5-phenyl-4-oxazolidinone to at least a pH of 11, introducing into the solution a salt selected from the group consisting of the salts of magnesium copper and iron and recovery from the resultant reaction mixture the said chelate.
6. The method of preparing 2-imino-5-phenyl-4-oxazolidinone-N,N'-magnesium which comprises adding to a solution of 2-imino-5-phenyl-4-oxazolidinone elevated to a pH of at least 11, a magnesium salt and recovering from the resultant mixture, the white precipitate therefrom.
7. The method of preparing 2-imino-5-phenyl-4-oxazolidinone-N,N'-copper which comprises adding to a solution of 2-imino-5-phenyl-4-oxazolidinone elevated to a pH of at least 11, a copper salt and recovering from the resultant mixture, the blue precipitate therefrom.
8. The method of preparing 2-imino-5-phenyl-4-oxazolidinone-N,N'-iron which comprises adding to a solution of 2-imino-5-phenyl-4-oxazolidinone elevated for a pH of at least 11, an iron salt and recovering from the resultant mixture the brown precipitate therefrom.
9. A pharmaceutical composition in dosage unit form including a pharmaceutical carrier and from 15 to 200 mg. of a metal chelate of 2-imino-5-phenyl-4-oxazolidinone selected from the group consisting of 2-imino-5-phenyl-4-oxazolidinone-N,N'-magnesium, 2-imino-5-phenyl-4-oxazolidinone-N,N'-iron.

40

45

50

zolidinone-N,N'-copper and 2-imino-5-phenyl-4-oxazolidinone-N,N'-iron.

10. A pharmaceutical composition as described in claim 9, said carrier being a solid carrier.
11. A pharmaceutical composition as described in claim 9, said carrier being a liquid carrier.
12. A pharmaceutical composition as described in claim 9, said carrier being a suppository base.
13. A pharmaceutical composition in dosage unit form comprising a pharmaceutical carrier and from 15 to 200 mg. of 2-imino-5-phenyl-4-oxazolidinone-N,N'-magnesium.
14. A pharmaceutical composition in dosage unit form comprising a pharmaceutical carrier and from 15 to 200 mg. of 2-imino-5-phenyl-4-oxazolidinone-N,N'-copper.
15. A pharmaceutical composition in dosage unit form comprising a pharmaceutical carrier and from 15 to 200 mg. of 2-imino-5-phenyl-4-oxazolidinone-N,N'-iron.
16. The method of stimulating the central nervous system in animals and human beings which comprises administering to the subject to be so stimulated a metal chelate of 2-imino-5-phenyl-4-oxazolidinone selected from the group consisting of 2-imino-5-phenyl-4-oxazolidinone-N,N'-magnesium, 2-imino-5-phenyl-4-oxazolidinone-N,N'-copper and 2-imino-5-phenyl-4-oxazolidinone-N,N'-iron.
17. The method of stimulating the central nervous system in animals and human beings which comprises administering 2-imino-5-phenyl-4-oxazolidinone-N,N'-magnesium to the subject to be so stimulated.
18. The method of stimulating the central nervous system in animals and human beings which comprises administering 2-imino-5-phenyl-4-oxazolidinone-N,N'-copper to the subject to be so stimulated.
19. The method of stimulating the central nervous system in animals and human beings which comprises administering 2-imino-5-phenyl-4-oxazolidinone-N,N'-iron to the subject to be so stimulated.
